Mallory Mc Marshall. Smithfield Virginia

Sc. 11775. (P. 1070)

The Schedule referred to in this Letter Patent and making part of the same containing a description of the invention of the said Mallory Mc Marshall himself of his improvement in the machine for cutting Stone & Slating.

To be known that of a Mallory Mc Marshall of Smithfield in the County of the State of Virginia and State of Virginia. Inventor of a new and useful improvement in the machine for cutting Stone and Slates, which is described as follows, reference being had to the annexed drawings, of the same being part of this application. — This machine consists of two posts A. B. placed apart the distance of the width of the gate and suspended together. On the inside of which posts are set, grooves or gins in which the gate slides up and down. — The gate C consists of four pieces of thin iron bound together forming a rectangular frame, except, which in an upright position is fastened, near the knife D, for cutting the stone, the cutting knife E is placed in a horizontal position in the rear of the posts, and is fixed with iron. A small iron plate F is suspended in the center in front of the machine, is let into the front of the posts. To this top of the gate is attached by a chain or cord a spring G, for drawing up the gate, which spring is fastened to an oblique stand and fastened to the posts. If the bottom of the gate is attached or bridle H, worked by the foot of the operator. — The operator takes a handle of stone in his right hand and brings it under the knife, he then with his foot bears down upon the treadle and forces down the gate and knife which cuts the stone. In the same his foot and the spring instantly draws up the gate and knife ready for another cut, which is made in a similar manner. — What I claim as my invention and which I desire to secure by Letters Patent consists in the before described machine for cutting stone.
